UNITED STATES PATENT OFFICE

147,105

DESIGN FOR A MOBILE SERVICE VEHICLE

Robert O. Borst, Pasadena, Calif.

Application November 2, 1945, Serial No. 123,418

Term of patent 3½ years

(Cl. D14—3)

To all whom it may concern:

Be it known that I, Robert O. Borst, a citizen of the United States of America, residing at Pasadena, in the county of Los Angeles, State of California, have invented a new, original, and ornamental Design for a Mobile Service Vehicle, of which the following is a specification, reference being had to the accompanying drawings, forming part thereof.

In the drawings:

Fig. 1 is a top plan view of a mobile service vehicle showing my new design, a portion of the dotted line showing being broken away for convenience of illustration;

Fig. 2 is a side elevational view of Fig. 1; and

Fig. 3 is a side perspective view showing the complete vehicle.

The characteristic features of my design are shown in full lines in the drawings.

I claim:

The ornamental design for a mobile service vehicle, as shown and described,

ROBERT O. BORST.
